CATHODE ASSEMBLY

Raymond B. Ayer, Verona, N. J., assignor to Radio Corporation of America, a corporation of Delaware

Application May 31, 1940, Serial No. 338,189

7 Claims. (Cl. 250—27.5)

My invention relates to cathodes for electron discharge devices, particularly to supports and current supply means for cathodes in such devices.

5 Transmitter tubes of the type shown in the Zottu et al. Patent 2,113,671, April 12, 1938, employ a cage type cathode comprising circularly arranged parallel straight filament wires. When these filament wires are of pure metals such as 10 tungsten or tantalum and are operated at temperatures as high as 2000° C. or above, the problem of insulatingly supporting the cathode in fixed spaced relation with the other electrodes is difficult. If mechanical supports are provided 15 at both ends of the cathode, provision must be made for expansion and contraction of the filament wires, and insulating bushings must be provided to withstand the high operating temperature and yet permit free longitudinal movement for the wires.

20 An object of my invention is a cathode with improved support means that will accurately fix the cathode in spaced relation with the other electrodes and will permit longitudinal expansion.

25 A more specific object of my invention is an improved cathode support for transmitter tubes of high power that is easy to assemble and will protect insulating spacers from the high operating temperatures of the cathode.

30 The characteristic features of my invention are defined in the appended claims and one preferred embodiment thereof is described in the following specification and shown in the accompanying 35 drawing in which Figure 1 shows in section my improved cathode and support mounted in a transmitter tube, Figure 2 is a longitudinal sectional view showing details of construction of my improved cathode support, and Figure 3 is an end view of the assembly shown in Figure 2.

40 The particular transmitter tube shown in the drawing comprises a water-cooled anode 1, coaxial with a screen grid 2, a control grid 3 and cathode 4. The wires of the grids and cathode 45 are straight and parallel, are circularly arranged, and lie in concentric cylindrical surfaces. The filament wires of the cathode are at their lower end 5 bunched together and joined as by arc welding or high temperature brazing.

50 Hollow lead-in conductors or pipes 6 and 7 sealed into the upper end of the envelope support the cathode and supply the heating current to the filament wires. On the inner ends of the pipes are carried concentric metal ring 8 and 55 metal plate or disc 10. Preferably the plate is

flat, although the plate may be convexed or concaved, and preferably the rim of the plate lies in the plane of the ring although it may be axially displaced with respect to the ring. The inner periphery of the ring is serrated with radial teeth or extensions 9 interleaved with serrations 11 on the outer periphery of the disc. The serrations may be rounded as shown, triangular in shape or of any desired configuration which can be easily formed in the ring and disc and fitted together without short circuit. Alternate filament wires 4 of the cathode are joined to the serration 9 on the ring, the other wires being joined to the serrations 11 on the disc. To join the filament wires to the serrations, it is preferred 15 to bore holes in the serrations normal to the plane of the ring and disc, with the holes arranged in a circle coaxial with the ring. The ends of the filament wires may then be inserted in the holes and, when brazed or welded 20 in place, stand normal to the plane of the ring and disc and accurately center the cathode in the tube.

According to one of the novel features of my invention, a cooling fluid is circulated in contact 25 with the rear surface of the ring 8 and disc 10, the cooling effect of the fluid being brought to the ends of the filament wires. Since the ends of the filament wires are kept cool the wires will not bow or buckle and the brazed connections 30 at the ends of the wires cannot be softened or loosened by heat. The ring 8 closes one end of a hollow annulus 12 comprising two telescoped and coaxial spaced tubular walls 13 and 14. The interior of the annulus communicates with 35 the interior of the lead-in pipe 6 and is joined gas and liquid tight to the end of the pipe. Pipe 6 has a central partition 15 that extends into the annulus and abuts liquid tight at its end against the inner surfaces of cylinders 13 and 14 and 40 ring 8. Cooling fluid, such as water, entering conductor 6 on one side of the partition 15 then flows into and around the annulus to the other side of the partition where it re-enters tube 6 and flows out. Pipe 7 is joined gas and liquid 45 tight to the rear surface of disc 10 and is provided with a central partition so that cooling fluid flowing inwardly along one side of the partition is projected against the rear surface of the disc and flows out along the other side of the 50 partition. Alternatively, of course, a small feed pipe could be passed into pipe 7 and terminated short of the rear surface of the disc 10 to provide the inlet or outlet passage within the pipe 7 for the cooling fluid. The inner end of the 55

pipe 7 and disc 10 is held coaxial with and in fixed spaced relation from the inner cylinder 14 of the annulus by an insulating bushing 16 of refractory insulating material, such as ceramic.

5 Since the bushing 16 lies between the water-cooled wall of cylinder 14 and pipe 7, and its end is shielded from the filaments by disc 10, its temperature may never rise above the temperature of the cooling fluid, and a tight or drive fit may 10 be made between pipe 7, bushing 16 and cylinder 14 since no provision need be made for expansion of the metal or insulating parts of the cathode support. A heat and electron shield 17 may, if desired, be mounted on the ring 8 to prevent 15 thermal and electron emission from the filament wires to the grid wires.

All metal parts of my improved cathode support may be made of copper, nickel, "Monel" or other easily machined metal, and because of their 20 mechanical simplicity are easily assembled. Good results have been obtained in making my improved cathode support with the ring 8 and disc 10 of nickel only $\frac{3}{16}$ " in thickness. The holes 25 in the serrations of the ring and disc are accurately bored on a drill press or lathe normal to the faces of the ring and disc and the parts then assembled. The filament wires of tungsten, about .05 inch in diameter, are then slightly tapered by caustic etching, inserted in the holes 30 and arc-welded on the under or water-cooled side of the serrations. Preferably the ends of the wires are pushed through the holes so that their 35 ends appear on the reverse side where they can be arc welded or brazed.

35 I claim:

1. A cathode assembly comprising a cylinder with two spaced concentric metal walls, means 40 for circulating a cooling fluid between the walls, a ring, serrated along its inner periphery, in good heat conducting contact with one end of the cylinder, a metal disc serrated along its periphery, in the plane of said ring and coaxial with the 45 ring, the serrations of the disc extending radially outward and between the serrations of the ring, means supporting the disc in insulated spaced relation from the ring, and a filament wire connected to each of the serrations.

2. A cathode assembly comprising an annulus, 50 a metal disc coaxial with the annulus, means for circulating cooling fluid against one side of said disc, a plurality of circularly arranged parallel filament wires, alternate wires being joined at one end to the other side of said disc and the 55 remaining wires being joined at one end of the

tubular annulus, said wires extending outwardly normal to the plane of said disc.

3. A cathode comprising a plurality of circularly arranged parallel filament wires, current supply means for one end of the cathode comprising a concentric metal ring and a plate, the outer periphery of the plate and the inner periphery of the ring being serrated with the serrations of the ring and plate interleaved, at least one filament wire joined to each serration. 10

4. A cathode assembly comprising an annulus with two telescoped spaced tubular walls, said walls being closed at their ends, means for circulating a cooling fluid between said walls, a pipe 15 extending into and coaxial with said annulus, a plate joined to the end of said pipe and fixed in a plane transverse to the axis of said annulus, an insulating bushing between the outer wall of the pipe and the inner wall of the annulus, a filament wire joined at one end to the plate and 20 a second filament wire joined to the end of said annulus, the other ends of the wires being joined together.

5. A cathode assembly comprising a coplanar ring and disc, means for circulating a cooling 25 fluid against one side of said ring, means for circulating cooling fluid against the corresponding side of said disc, a plurality of filament wires on the other side of the ring and disc, some of the wires being joined to the ring, the remainder 30 of the wires being joined to the disc, the other ends of the wires being connected together.

6. A cathode assembly comprising a concentric ring and plate, a hollow annulus joined to one side of said ring, a pipe joined to one side of 35 said plate, interleaved serrations along the opposing peripheries of the ring and disc, filament wires inserted at one end in holes in said serrations, the opposite ends of said filament wires being mechanically and electrically connected. 40

7. An electron discharge device comprising a tubular anode and a coaxial cathode, said cathode comprising straight parallel circularly arranged wires lying in a cylindrical surface coaxial with said anode, said wires being mechanically joined 45 together at one end, means for rigidly supporting each wire in said surface comprising two hollow lead-in conductor pipes, a metal ring joined to the inner end of one pipe, a metal plate coaxial with the ring joined to the end of the other pipe, 50 the other ends of the wires being secured to said ring and disc, and an insulating spacer for rigidly holding said ring and disc in fixed spaced relation.
